W. H. FLOOD ET AL

ELECTRODE HOLDER

Filed May 14, 1921

UNITED STATES PATENT OFFICE.

WALTER H. FLOOD, OF TOOTING, LONDON, AND DONALD TRENTHAM SMOOT, OF WEST DULWICH, LONDON, ENGLAND, ASSIGNORS TO ELECTRIC ARC CUTTING AND WELDING COMPANY, OF NEWARK, NEW JERSEY.

ELECTRODE HOLDER.

Application filed May 14, 1921. Serial No. 469,560.

To all whom it may concern:

Be it known that we, WALTER HERBERT FLOOD and DONALD TRENTHAM SMOOT, subjects of the King of Great Britain, residing at 56 Lucien Road, Tooting, London, and 175 Clive Road, West Dulwich, London, England, respectively, have invented certain new and useful Improvements in Electrode Holders, of which the following is a specification.

This invention relates to electrode holders and especially to that class of holders suitable for use in arc welding, cutting and like operations.

In general the invention comprises a tube within which is seated a plug bearing a pair of spring arms, to the outer end of which are secured jaws for gripping an electrode, means being provided within reach of the thumb on the hand grasping the tube to release the electrode from the holder.

It is an object of this invention to make a holder of this character as small and compact as possible.

It is a further object of this invention to provide means for securely retaining the electrode within the holder and to prevent accidental loosening thereof.

It is a still further object of the invention to provide a shield operable by the thumb on the hand grasping the holder to release the electrode from the holder.

Other and further objects will appear after reading the following specification and claims in connection with the accompanying drawings in which—

Figure 1 is a plan view of our electrode holder.

Figure 2 is a section on the line 2—2 of Fig. 1.

Figure 3 is a plan view of the shield and its operating shaft.

Figure 4 is a section on the line 4—4 of Fig. 3.

Figure 5 is a section on the line 5—5 of Fig. 1.

Figure 6 is an isometric drawing of the operating shaft removed from the shield, and

Figure 7 is a side elevation of the jaws of the holder.

Now referring in detail to the various figures, 1 indicates a non-conductive tube

preferably made of fibre within which is frictionally retained a metallic plug 2 preferably made of brass. Within the plug is a bore 3 forming a cable socket in which the bared end of a cable may be sweated or, if preferred, retained in place as by screws 4, 4. The end of the tube adjacent the plug is threaded and screwed thereinto is a fibre cap 5 to finish off the appearance of the holder and to prevent accidental contact with the cable end or plug. The plug has a tongue 6 to which are riveted pairs of springs 7, 7 and 8, 8, although it is to be understood that if desired one of the leaf springs of each pair may be replaced by a copper strip for greater conductivity. To the otherwise free ends of the leaf springs are secured a pair of cooperating jaws 10 and 11, these jaws being removably secured to the springs by means of screws 9 to enable renewal of the jaws as those in use become burnt or pitted. The jaws are made of some good conductive material but preferably of bronze to resist corrosion, pitting and burning and in order to firmly retain an electrode in place between the jaws, the jaw 10 is serrated so as to form teeth 12. The jaw 11 does not have any teeth but is formed with a longitudinal boss 30 between which and the teeth 12 of the jaw 10, the electrode may be placed. The jaw 10 is also provided with a longitudinal recess 31 within which the boss 30 of the jaw 11 may seat when there is no electrode between the jaws, these jaws being normally urged toward one another by the springs 7, 7 and 8, 8.

To effect a separation of the jaws, the fibre tube is slotted as at 13, and resting against the bottom of the slot is a cam member 14, said member being rounded at 15 at the portions where it bears in the slots and being squared as at 32 between the confines of the leaf springs. It will now be apparent that upon rotation of the cam member, that the leaf springs will be separated to separate the jaws. In order to rotate the cam member the same is provided with shouldered portions 16 and 17 retained in a shield 18 preferably made of fibre. The shield has an aperture 19 somewhat elliptical in shape. A pair of brass strips 20 secured to the shield by rivets 21 retain the

- cam member securely within the shield. The shield is recessed slightly as at 22 to position the thumb on the shield when it is desired to tilt the same in order to separate 5 the jaws. When the shield is released, the springs serve to restore the same to normal position as well as tensioning the jaws toward each other. A pin 23 passes loosely through the leaf springs and is secured in 10 place in the tubular handle by cotter pins 24 passing through holes 25 in the pin and said pin holds the cam member 14 from moving out of the slots 13. The cam member is rounded at 26 to prevent any sharp 15 edges on the cam member from wearing or bending the pin when the cam member is rotated. The slotted end of the tube has an internal taper 24 to permit spreading of the leaf springs. While the shield is shown 20 rather small, it may be made of any desired size sufficient to protect the hand of the operator from the heat of the welding or cutting arc or from molten material. If desired the shield may be provided with 25 plates 27 of celluloid or the like bearing the indication "Push" thereon, and the handle may be provided with a name plate 28 of similar material embedded within a recess 29 in the handle.
- 30 From the above construction, we have provided a small, neat and compact holder, with means within reach of and manipulated by the thumb of the operator for effecting a quick release of the electrode held 35 by the jaws of the holder, or for permitting the insertion of a new electrode between the jaws.
- Having thus described our invention what we claim is:
- 40 1. An electrode holder comprising a non-conductive tube, a plug within said tube, a set of leaf springs secured to said plug and extending beyond the tube, a pair of metallic jaws secured to the otherwise free ends of 45 said springs, said springs normally urging said jaws together, means on said jaws for gripping an electrode, and means carried by the tube for effecting the separation of the jaws.
- 50 2. An electrode holder comprising a non-conductive tube, a plug within said tube, leaf springs secured to said plug and extending beyond the tube, a pair of metallic jaws secured to the otherwise free ends of 55 said springs, said springs normally urging said jaws together, means on said jaws for gripping an electrode, and means for effecting the separation of the jaws comprising a cam member, said cam member having 60 flat surfaces adapted upon rotation thereof to engage and separate the leaf springs to thereby separate the jaws, and means to rotate said cam member.
- 65 3. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member having flat surfaces adapted upon rotation thereof to engage and separate the leaf springs to thereby separate the jaws.
- 70 4. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member, said cam member having flat surfaces adapted upon rotation thereof to engage and separate the leaf springs to thereby separate the jaws.
- 75 5. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 80 6. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 85 7. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 90 8. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 95 9. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 100 10. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 105 11. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 110 12. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 115 13. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 120 14. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 125 15. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.
- 130 16. An electrode holder comprising a non-conductive tube, a plug within said tube, leaf springs secured to said plug and extending beyond the tube, a pair of metallic jaws secured to the otherwise free ends of said springs, said springs normally urging said jaws together, means on said jaws for gripping an electrode, and means for effecting the separation of the jaws comprising a cam member rotatable in a slotted portion of the tube, said cam member having flat surfaces adapted upon rotation thereof to engage and separate the leaf springs to thereby separate the jaws.

- the jaws, a pin secured in the tube restraining the cam member against longitudinal movement in the slot, and a shield secured to the cam member to permit rotation thereof 5 upon manipulation by the thumb of the hand grasping the tube.
7. An electrode holder comprising a part adapted to be grasped by the hand of the operator, electrode gripping jaws, and a shield therebetween adapted to shield the hand of the operator and means operated by movement of the shield to separate the jaws.
8. An electrode holder comprising a part adapted to be grasped by the hand of the operator, electrode gripping jaws, and a shield therebetween adapted to shield the hand of the operator and means operated by a tilting movement of the shield to separate the jaws.
- 10 9. An electrode holder comprising a part adapted to be grasped by the hand of the operator, normally closed electrode gripping jaws, and a shield therebetween adapted to shield the hand of the operator, means operated by movement of the shield to separate the jaws, and means to restore the gripping jaws to normal position and to re-
- store the shield to initial position after jaw moving operation.
10. An electrode holder comprising a non-conductive member with leaf springs secured to said member and projecting beyond the end thereof in substantially two parallel sets spaced apart, jaws carried by the free ends of the springs, said springs 35 normally urging the jaws together and means carried by the member for separating the jaws.
11. An electrode holder comprising a non-conductive member having a recess opening 40 at one end thereof, leaf springs in said recess, secured within said member in spaced relationship and extending beyond the end thereof, jaws carried by the free ends of the springs, said springs being adapted to 45 normally urge the jaws together and means carried directly by the member for separating the jaws.

In testimony whereof we have hereunto set our signatures this 19th day of April, 50 1921.

W. H. FLOOD.
DONALD T. SMOOT.
